PORATION OF OHIO

CAN AND CAN-OPENING DEVICE

Application filed February 11, 1928. Serial No. 253,728.

Our invention relates to the type of can with a taggers tin closure, which has a slip cover provided with a cutter knife which pierces the taggers tin of the top closure and by the rotation of the cover cuts out a circular disc which exposes the contents of the can.

Broadly speaking, this type of can is old and well known in the art, being first disclosed in the Williamson Patent #378,849, with some additional improvements being shown in the later Williamson Patent #652,067. This type of can has a slip cover for use after the taggers tin of the sealed top has been removed. The cover has a radial slot near its peripheral edge and within the slot is slidably mounted a cutter which has a knife portion and a handle portion with which the knife may be moved along in the slot from a peripheral pocket in the slip cover, in which the knife is inoperative, to a position in which it pierces the taggers tin.

Our combination has all the well known features of such combinations. It has been found that cans of this type frequently present a source of danger to the person who opens them and uses them after they have been opened, because the thin annular rim of taggers tin left in the can top is rough and quite likely to inflict a serious scratch or cut. It is the object of our invention to provide a cutter and a can which will have a smooth inner edge of the taggers tin which remains after the circular piece has been removed.

More specifically it is the object of our invention to provide a can having an annular indentation so arranged with reference to the taggers tin which is cut out that the annular rim will be crimped or folded down against it with a perfectly smooth joint. It is also our object to provide a cutting knife which will be curved across the blade on a smaller radius than the curve of the can so that the outer surface of the curved portion will operate to crimp the outer annular rim smoothly.

The above and other objects to which reference will be made in the ensuing disclosure we accomplish by that certain combination and arrangement of parts of which we have shown a preferred modification.

In the drawings:

Figure 1 is a plan view of the slip cover with parts in section showing the cutter in operative position.

Figure 2 is a plan view of the slip cover with parts in section showing the cutter in inoperative position.

Figure 3 is a sectional view taken along the lines 3—3 in Figure 2 showing the cutter mounting.

Figure 4 is a vertical sectional view of a can with the cutter in operative position having pierced the taggers tin lid of a can.

Figure 5 is a sectional view of a complete can with the slip cover in inoperative position and with the taggers tin lid reinforced with concentric corrugations.

Figure 6 is a sectional view of a can with the taggers tin end in place, showing one type of bead which we have found satisfactory.

Figure 7 is a sectional view showing of the can shown in Figure 6 prior to the crimping on of the end.

Figure 8 is a perspective view of the cutter knife detached from the slip cover and in inverted position.

Figure 9 is a sectional view of a can after the crimping on of the taggers tin end, the beading being of a different size than that shown in Figure 6.

Figure 10 is a sectional view of a can prior to the crimping on of the taggers tin end, the beading being similar to that shown in Figure 9.

The can is formed by side walls 1 with a bottom 2 which is secured to the side walls by crimping together the outer peripheral edge 3 of the bottom against the crimping flange 4 of the side walls. This is done in the usual

manner and forms no part of our invention. Material is then filled into the can and the circular disc 4^a of taggers tin is laid over the top crimping flange 5 and crimped over as indicated. We preferably provide reinforcing corrugations 4^b in the taggers tin disc. Either during the crimping of the taggers tin to the can walls, or prior to this, an annular inwardly grooved bead 6 is formed in the can walls. This bead serves an important function in the operation of the opening of the can and will be hereinafter described.

The slip cover which is formed by a circular disc of tin 7 with a downturned annular flanged lip 8, has a slot 9 extending radially therein from a position about three fourths of distance from the center of the slip cover to the rim to a position about an eighth of an inch from the rim. The dimensions of this slot will determine the range of movement of the cutter within the slot and the dimensions are calculated so as to limit the movement of the cutter so that the knife 10 of the cutter will only have a range of movement from the pocket 11 formed in the annular lip 8 of the cover to such a position that it will, when inserted through the taggers tin, bear against the round angular shoulder of the beading and crimp the thin outer peripheral wall of the rim of taggers tin which is not cut out, against the shoulder so as to leave a non-jagged opening.

The pocket 11 is provided so that when the can is shipped there will be no likelihood of the knife piercing the taggers tin lid prematurely. At the peripheral edge of the slip cover there is an upturned bead 11^a and the surface of the cover is formed up in a flat plane level with the top of the beading so that the cutter can slide readily. The cutter is inserted in the slot from the under side of the slip cover and the two wings 12 which, during the inserting, are bent into parallel alignment, are then bent down to cause the cutter to be retained within the slot and also to provide a handle for pushing the cutter knife from the inoperative position within the pocket into cutting position.

It will be preferable that the knife 10 be provided with blunt side edges and with the blade curved both across the width of the blade and in alignment with its length. The tip 13 of the cutter should also be slightly beyond the position of vertical alignment with the angle at which the cutter blade extends from the cutter body.

The operation of our novel can opening device is as follows: The person who is about to open the can removes the slip cover from the can and using the thumb nail pushes the cutter radially inward to the inner end of the slot. The slip cover is then replaced on the can and pressed downwardly to cause the tip 13 of the knife to pierce the taggers tin. Then while holding the can firmly in

the hands the slip cover is rotated one complete revolution and a circular disc is cut out. The annular rim of the taggers tin which is not cut out is crimped against the round curve of the beading so that when the disc is removed there remains a perfectly smooth opening in the top of the can.

The cooperation of the beading and the tip of the cutter knife is quite essential for the formation of a perfect smooth, non-jagged opening and while the shape of the cutting blade will preferably be in accordance with the foregoing description, a satisfactory job may be done by using a flat knife blade. With the curved knife blade and with blunt edges on the sides of the blade, the crimping effect is more perfectly accomplished, as the outer surface of the curved blade crimps the outer annulus of the taggers tin end smoothly against the bead.

While we have illustrated preferred structures, modifications in the specific shapes and sizes of the parts indicated will readily occur to those skilled in the art, and insofar as they accomplish equivalent functions by the mere change of size and shape of the parts shown in our combination, we consider such modifications within the scope of our invention.

It will further be apparent that without the slip cover and knife the annular beading will provide a shoulder against which the annulus of any type of severable cover may be formed down with other types of can openers.

Having thus described our invention, what we claim as new and desire to secure by Letters Patent, is:

1. A can having a severable lid attached thereto and having a slip cover carrying a cutter knife, said cutter knife having a downwardly projecting blade, and said can having a convex rib formed on the inner walls thereof extending to such position that when the slip cover is rotated carrying said blade in a circumferential path around the lid that the outer annulus of the severable lid will be formed down against said annular projection thereby providing a non-jagged opening.

2. A can having a severable lid attached thereto and having a slip cover carrying a cutter knife, said cutter knife having a downwardly projecting blade, and said can having a convex rib formed on the inner walls thereof extending to such position that when the slip cover is rotated carrying said blade in a circumferential path around the lid that the outer annulus of the severable lid will be formed down against said annular projection thereby providing a non-jagged opening, said blade being of triangular shape with blunt sides.

3. A can having a severable lid attached thereto and having a slip cover carrying a

cutter knife, said cutter knife having a downwardly projecting blade, and said can having a convex rib formed on the inner walls thereof extending to such position that when the slip cover is rotated carrying said blade in a circumferential path around the lid that the outer annulus of the severable lid will be formed down against said annular projection thereby providing a non-jagged opening, said blade being curved laterally and lengthwise.

SUMNER M. MANLEY.
HENRY HEITLAGE.

cutter knife, said cutter knife having a downwardly projecting blade, and said can having a convex rib formed on the inner walls thereof extending to such position that when the slip cover is rotated carrying said blade in a circumferential path around the lid that the outer annulus of the severable lid will be formed down against said annular projection thereby providing a non-jagged opening, said blade being curved laterally and lengthwise.
